UNITED STATES PATENT OFFICE.

LEWIS H. FISCHER, OF NORMAN, OKLAHOMA.

DEVICE FOR TRUING CAPS OF FRUIT-JARS.

No. 893,838.

Specification of Letters Patent.

Patented July 21, 1908.

Application filed May 21, 1907. Serial No. 374,892.

To all whom it may concern:

Be it known that I, LEWIS H. FISCHER, a citizen of the United States, residing at Norman, in the county of Cleveland, Oklahoma, have invented a new and useful Device for Truing Caps of Fruit-Jars, of which the following is a full, clear, and exact description, reference being had to the accompanying drawings.

10 Fruit jars are provided with screw-threaded sheet-metal caps, the lower edge of the caps being flanged to correspond to the shape of the jar, and adapted to close against a sheet-rubber gasket to seal the jar air-tight.

In unscrewing the caps from the jars, many persons force a knife or other instrument under the edge of the flange to break the adhesion of the cap to the gasket or jar, 20 thus bending the flange out of normal shape so that it will not again form an air-tight closing of the jar.

The object of this invention is to provide a cheap and simple means for straightening 25 and truing the flanges of the caps.

Referring to the drawings: Figure 1 is a plan view of a portion of the improved device. Fig. 2 is an elevation view of the same portion. Figs. 3 and 4 are plan and edge 30 views, respectively, of a part of the device. Fig. 5 is an elevation view of a cap, showing the cap flange bent or distorted out of normal shape. Fig. 6 shows the invention in use.

35 Referring to the several figures, in all of which like characters of reference designate like parts, the improved device comprises a cast-metal main portion 7 having integral feet 7^b so that it may be secured by screws to a board 8, table, or other suitable support. The upper or head portion 7^c of this member 7 is shaped and screw threaded like the upper end of a fruit-jar, so that the cap 9 may be screwed onto it.

45 In truing up the caps 9 they are first screwed tightly onto the head 7^c of the member 7, and then operated upon by a clamping member or tool 10, as shown in Fig. 6. This clamp 10, which is shown separately in Figs. 50 3 and 4, comprises an elastic C-shaped portion 10^b, the terminals of which are provided with integral handles 10^c, so that it may be

closed grippingly around the cap 9. The C-shaped portion 10^c of the clamp member 10 is provided interiorly with screw threads of a 55 gage to snugly fit exteriorly over the threads formed in the sheet-metal cap 9 when closed around said cap by gripping the handles 10^c together. The lower edge of the C-shaped portion 10^b of the clamp 10 is flanged, as at 60 10^d, so that when clamped and screwed down over the cap 9 it presses the flange 9^b thereof down firmly and truly against the surface 7^d of the member 7, thus straightening and re-forming said flange. 65

In screwing the cap 9 onto the form or head 7^c all dents and abnormal formations in the threads thereof will be pressed out, and the forcible action of the clamp 10 on the outside of said cap 9 will press the threads 70 back into normal form.

As a means of exerting greater force upon the cap 9 by the clamp 10 than can be exerted by gripping the handles 10^c, a screw-threaded rod 11 is secured pivotally by a pin 75 12 to one of said handles and extends through an opening in the other handle, the free end of said rod 11 being provided with a screw-threaded thumb-nut 13. This arrangement of parts places the nut 13 in position where it 80 may be screwed up by the thumb and finger of the hand simultaneously with the gripping of the handles 10^c together, so that in cases requiring extra force to press the cap into proper shape said nut 13 and the rod 11 may 85 be employed.

The foregoing being a full, clear, and exact description of the invention, what I claim and desire to secure by Letters Patent is:—

1. In a device of the class described, a C- 90 shaped clamping member having its clamping surface screwthreaded for engagement with the exterior surface of a screwthreaded cap, the terminals of said clamp being provided with hand-holds for effecting its clamping 95 engagements.

2. In a device of the class described, a die member adapted to have a cap placed over it, a C-shaped member adapted to engage the exterior of said cap, the terminals of said C- 100 shaped member having hand-holds for closing it, means operable by the thumb or finger of the hand for increasing the closing force of said C-shaped member.

3. In a device of the class described, a screwthreaded die member adapted to have a jar-cap screwed onto it, an interiorly-screw-threaded C-shaped clamping member adapted to engage the exterior of said cap, said C-shaped member being provided with levers or hand-holds for closing it, one of said levers having a screwthreaded extension

through the opposite lever, said extension having a screwthreaded thumb-nut. 10

Witness my hand this sixth day of May, 1907.

LEWIS H. FISCHER.
